HOUSING FOR SIGNALING APPARATUS

Max C. Nelson, Lakewood, Ohio, assignor, by mesne assignments, to the United States of America as represented by the Secretary of the Navy

Application November 29, 1957, Serial No. 699,875

4 Claims. (Cl. 240—11.2)

This invention relates to signaling beacons and more particularly to a unitary protective housing for assembling the signaling equipment.

For direct visual communication between naval vessels, the flashing light system of signaling is employed to a great extent and the usual source of this type of signal is an incandescent or carbon arc lamp. It is customary in the naval service to assign the upkeep of such signaling apparatus to a signalman who is required to check and clean the equipment daily in order to insure proper operation of the apparatus. In such prior signaling apparatus, the transformers and other power supply equipment, which is auxiliary to the lamp and shutter assembly is usually not housed therewith and consequently substantial floor area is required for the entire signaling apparatus assembly. Additionally, unless properly protected the delicate operating elements of the signaling apparatus, such as the lens and reflector, may be deteriorously affected by salt spray which in time not only reduces the operating efficiency of the apparatus but often requires replacement of parts.

Accordingly, it is the broad object of this invention to provide a single unitary protective housing for the signal transmitting assembly and its auxiliary power transmitting equipment.

Another object is to provide a single unitary protective housing for signal or searchlights and its auxiliary equipment which is strong and compact, and yet is arranged to provide ready access to its parts for inspection, repair, or replacement.

Other and further objects of the invention will be more readily understood from the following description taken in connection with the drawings, wherein:

Fig. 1 is a side elevational view of the housing with a portion of its shell removed to show details; and

Fig. 2 is a rear elevational view of the housing; and

Fig. 3 is a view taken along the line 3—3 of Fig. 1; and

Fig. 4 is a perspective view of the lower portion of the housing; and

Fig. 5 shows a detail of the apparatus.

Referring to Figure 1 the housing is indicated generally at 10 and consists of a lower power transmitting compartment 11, a central signaling compartment 12 and a protective cover compartment 13. The housing is formed by bottom pan 14 which is supported at floor level by means of a transverse channel and angle iron indicated at 15 and 16 respectively. An outer shell 17 has its lower edge portion secured preferably, as shown, to the outer wall of the pan 14 and has its upper edge terminating about midway of the housing. The shell 17 is not a complete cylinder but as shown in Figure 4 is slotted at its rear face and further arranged to provide vertical edge portions 18 between which are received risers 19—19.

The risers 19—19, as shown in Fig. 1, extend vertically of both compartments 11 and 12 and, as shown clearly in Fig. 4, have inner portions which are positioned

2

within the shell 17. The inner portions are bent outwardly at 20 and have their outer edges in contact with the inner wall of shell 17 to form vertical spaces 21 which may be provided with vertical strengthening ribs 22 as shown. The risers 19 are preferably secured to the shell 17 by welding or bolting the vertical edge portions 18 of the shell thereto to provide a rigid structure. In effect, the risers provide a box-like chamber which has an open outer end embraced by a rectangular frame formed by vertical angle irons 23—23 and upper and lower angle irons 24 and 25 which are apertured as shown to permit removable securement of the housing to a wall and permit access to the box-like chamber as desired.

The box-like chamber provided by the risers 19—19 is provided with plurality of horizontal shelves 26 and 27, shown in Fig. 4 which are secured to the risers 19 to extend horizontally inwardly of the shell 17 and have their inner ends supported by vertical posts 28—28. These shelves function to receive transformers, reactors, condensers, etc., indicated by dashed lines in Fig. 2 and which are used in transmitting power to the lamp which is also supported between the risers 19 but disposed above the shelves and within the signaling compartment as will now be described.

The signaling compartment 12 is formed immediately above the equipment compartment 11 by means of similar upper and lower generally dish-shaped partitions 30 and 31 shown in Figs. 1 and 3 and in detail in Fig. 5 which are arranged to receive and clamp therebetween an outer window indicated at 32 and a lens indicated at 33. The lower partition 31 is inverted to complement the upper partition 30 and both are developed or cut from metal spinnings. As shown in Fig. 5, each partition 30 and 31 is provided with an irregular cutout section which is defined by an inner vertical U-shaped flange 35 and an outer slotted portion defined by lines 36—36 with similar intermediate triangular shaped open areas which are defined generally by lines 37 and 38 and which merge into narrow slots 39.

The cutout sections of the partitions 30 and 31 permit their being received by the inner end portions 20 of the risers 19 as shown in Fig. 4 while the solid area of the partitions permit the window 32 and lens 33 to be held therebetween. To this end each partition is formed as shown in Fig. 1 with an outer annular vertical flange or step 40 for receiving the window 32 and an inner annular vertical flange or step 41 for receiving the lens 33. The window is maintained in place by a lower annular band 42 and a flange 43 of a baffle element in the cover section which will be described later. The lens 33 is maintained in place by upper and lower bands 44—44.

The window 32 is preferably formed of arcuate segments of substantially 220° and may have a wire mesh (not shown) disposed therebetween. Similarly, the lens is formed of arcuate segments of substantially 220° so that a large sector of the signal compartment of the housing is open to provide for omni-directional signaling. To effect this signaling, a signal lamp 50 is disposed within the central compartment 12 and has vertical posts 51 which are supported at the front ends of upper and lower U-shaped arms 52—52 which have their rear ends connected to a carrier bar 53 as shown in Fig. 3. The carrier bar 53 is notched at 54—54 as shown in Fig. 2 to be slidable on horizontal ribs 55—55 which are mounted at the upper end portions of the risers 19—19. This arrangement permits the lamp 50 to be readily inserted into compartment 12 or removed therefrom by access through the open rear end of the housing. Arcuate plates 56 close compartment 12.

The cover compartment of the housing is arranged to permit the dissipation of gases or air formed within the

housing while preventing the entry of water spray. To this end the cover is made up of an inner inverted dish-shaped baffle indicated generally at 60, having an annular depending flange 43 heretofore referred to and disposed about the step 40 of the upper clamping element 30 and which is provided with a central opening 61. An outer dome 62 is spaced from the baffle 60 by an annular screen 63 and the dome 62 provides an annular opening 64 with the flange 43 of baffle 60 permitting passage of air or gases from the housing compartments to the exterior of the housing. A drain pan 65 may, as shown, be disposed below the opening 61 by means of hangers 66 which are secured to the dome 62. The vertical spaces 21 shown in Fig. 4 are in communication at their upper ends with the upper compartment 13 and function to dissipate heat formed in compartments 11 and 12.

While there has been described a preferred embodiment of the invention, it will be obvious to those skilled in the art that various changes and modifications may be made therein within the scope of the invention, which is to be limited only by the appended claims.

What is claimed is:

1. A housing for signal equipment which comprises an upright shell having a closed base and an open upper end, a slotted opening in the shell providing spaced vertical edges, a pair of opposed and spaced vertical risers extending through the opening in parallel relationship, one of said risers being mounted adjacent one of the vertical edges and the other being mounted adjacent the other vertical edge providing an access opening of substantial area, a lower horizontal partition mounted at the upper end of the shell providing with the base a lower compartment for receiving power transmitting equipment through said access opening, an upper horizontal partition spaced from the lower partition, an arcuate window extending horizontally between said risers in op-

posed relation to said access opening, said window being held between said partitions providing therewith a central compartment for signal equipment, a lens spaced inwardly from said window and held between said upper and lower partitions in spaced relation with said window, a cover having an annular depending flange providing an annular space with said upper partition and an apertured ring-like baffle disposed between the upper partition and the cover whereby heated air from the central and lower compartments may exit through the annular space but the entry of water spray into the compartments is prevented.

2. Apparatus as in claim 1 further characterized by said risers extending upwardly to a line adjacent said upper partition to permit the central compartment to receive signal equipment through the access opening.

3. Apparatus as in claim 1 further characterized by lateral extensions on said risers disposed outwardly thereof of providing vertical passageways in communication with the upper compartment for the dissipation of heat from the central and lower compartments.

4. Apparatus as in claim 2 further characterized by lateral flanges extending outwardly of each riser with each flange having a vertical edge abutting the inner wall of the shell and the inner face of the window to provide vertical passageways in communication with the upper compartment for the dissipation of heat from the central and lower compartments.
